Des. 355

Gardner Gilson of Boston, Mass.
Letter Patent No. 355 dated Mar. 4, 1851.

The Schedule referred to in these Letters Patent, and making part of the same.

To all persons to whom these Presents shall come:

Be it known,

that I, Gardner Gilson, of Boston, in the County of Suffolk & State of Massachusetts, have invented, or produced, a new and original design for a register for furnaces &c. and I do hereby declare that the said new design is fully described and represented, in the following specification and accompanying drawing, to which reference is herein after made.

My new register is of rectangular form, as shown in the drawing, which is a plan, or top view, of the same, and has a smaller rectangle, formed by the bars b, b, b, b, placed within its sides. The space between the outer edge or surface a, a, a, a, of the register, and the rectangle b, b, b, b, is ornamented with the circular bars and apertures c, c, &c. these bars or rings, being connected to each other by the short straight bars d, d, &c. The space between the larger rings, is occupied by the curved bars e, e, &c. forming the diamond shaped apertures f, f, &c.

the curved spaces g, g, &c. between said bars and rings, and the elongated, opening j, in one of the longer bars a.

In the centre of the register is the ring h, h, - from the inner edge of this ring proceed the five curved bars i, i, &c. forming a five pointed star, and leaving the star shaped aperture k, in the centre of the register, and the oval shaped spaces l, l, &c. between said ring and bars.

From the outer edge of the ring h, h, curved bars or branches run to the bars b, b, b, b, forming the irregular curved apertures m, m, m, &c. the whole forming openings for the passage of the heat.

Having thus described my new design, I will state my claim as follows:

What I claim as my invention, or production, and desire to have secured to me by Letters Patent, is the new design herein above described, for a register of rectangular form, having within its sides a smaller rectangle, the space between the two being ornamented with the circular and diamond shaped lattice work, shown in the drawing, the inner rectangle being ornamented with irregular curved bars or branches, running from its sides to a ring in its centre, which encloses a five pointed star, with curved sides, the whole forming a lattice work, for the passage of the heat, all as herein above described.
